UNITED STATES PATENT OFFICE.

CHARLES F. MORSE, OF NEW YORK, N. Y.

INVISIBLE-PICTURE CARD.

No. 901,723.

Specification of Letters Patent.

Patented Oct. 20, 1908.

Application filed May 29, 1907. Serial No. 376,385.

To all whom it may concern:

Be it known that I, CHARLES F. MORSE, a citizen of the United States of America, and a resident of the city, county, and State of 5 New York, have invented certain new and useful Improvements in Invisible-Picture Cards, of which the following is a specification, reference being had to the accompanying drawings, forming a part thereof.

10 My invention relates to invisible-picture cards, and consists in a card containing thereon an invisible impression, and also provided with a developer which may be employed for the purpose of developing 15 such invisible impression whereby it may become visible.

The developer is preferably soluble in water. By the simple act, then, of immersing the card as a whole in water, such developer will be carried over to the invisible 20 impression, and the same will be developed thereby without any further act upon the part of the operator.

I conveniently produce the invisible 25 impression upon the central portion of a card, and surround this portion with a darker portion which contains the developer, said darker portion forming a mat or frame for the picture when developed.

30 In the drawing accompanying this application I have shown a card of this character, in which the central blank portion *a* forms a panel in which the invisible impression may be arranged, the outer darker 35 portion *b* being the part which contains the developer.

In the drawing: Figure 1 shows a card of this character before it has been immersed in water, and hence before the picture has 40 been developed, and Fig. 2 is a face view of such a card after such development.

Any suitable materials may be used for the invisible impression and for the developer, and I make no claim herein to any specific 45 materials for this purpose. In a co-pending application I have described an improvement in the art of invisible printing, which consists in employing yellow prussiate of potash as one of the materials, and a material 50 in which iron is included, such as

chlorid of iron, for the other. If a card having an invisible impression thereon, printed with yellow prussiate of potash and having a surrounding surface containing chlorid of iron, be immersed in water, the 55 effect will be that the chlorid of iron will be caused to immediately attack the yellow prussiate of potash, and the impression will be developed to a visible picture.

What I claim is:

1. A sheet or card containing on a portion of its surface an invisible impression, and upon another portion of its surface a developer for such impression.

2. A sheet or card containing an invisible 65 picture upon one portion of its surface, and upon another portion of its surface a developer therefor.

3. A sheet or card containing an invisible 70 picture upon its surface, and a developer upon a portion of its surface surrounding the said invisible picture.

4. A sheet or card having a light central portion having thereon an invisible picture, and a darker surrounding portion containing 75 a developer for the said picture.

5. A sheet or card containing on a portion of its surface an invisible impression, and upon another portion of its surface a developer for such impression, said developer 80 soluble in water.

6. A sheet or card containing an invisible 85 picture upon one portion of its surface, and upon another portion of its surface a developer therefor, said developer soluble in water.

7. A sheet or card containing an invisible 90 picture upon its surface, and a developer upon a portion of its surface surrounding the said invisible picture, said developer soluble in water.

8. A sheet or card having a light central portion having thereon an invisible picture, and a darker surrounding portion containing 95 a developer therefor, said developer soluble in water.

C. F. MORSE.
